RAKE HEAD ATTACHABLE TO A GOLF CLUB
SHAFT FOR SMOOTHING SAND IN A BUNKER
AND THE LIKE

Charles Albert Osborn, 203 Wendover Road,
Staines, England

Filed June 19, 1972, Ser. No. 264,059

Claims priority, application Great Britain Jan. 31, 1972

Term of patent 14 years

Int. Cl. D8—05

U.S. Cl. D8—13

FIG. 1 is a perspective view of a rake head, attachable to a golf club shaft for smoothing sand in a bunker and the like, showing my new design;

FIG. 2 is an elevational view thereof from one side;

FIG. 3 is an elevational view thereof from the other side.

I claim:

The ornamental design for a rake head attachable to a golf club shaft for smoothing sand in a bunker and the like, as shown.
